UNITED STATES PATENT OFFICE.

HENRY SCHMITT, OF DETROIT, MICHIGAN.

PISTON.

Application filed October 6, 1919. Serial No. 328,807.

To all whom it may concern:

Be it known that I, HENRY SCHMITT, a citizen of the United States of America, residing at Detroit, in the county of Wayne and State of Michigan, have invented certain new and useful Improvements in Pistons, of which the following is a specification, reference being had therein to the accompanying drawings.

10 This invention relates to an improved piston for engines and its object is to provide a piston which is so constructed as to obviate the necessity for the use of piston rings. A further object of the invention is to so construct the piston as to permit the walls thereof to yield and thus closely contact the cylinder wall during use, without weakening the walls of the piston, and further to provide such a piston with means for preventing leakage past the piston through slots in the walls thereof which provide the yielding action to said walls. It is also an object of the invention to provide certain other new and useful features in the construction and arrangement of parts, all as hereinafter more fully described.

15 With the above and other ends in view the invention consists in forming the wall of a piston with a longitudinal groove of a depth 30 to permit a contraction of the wall by the yielding action of the walls of the groove, and further consists in the other matters hereinafter set forth, all as more particularly pointed out in the appended claims, reference being had to the accompanying drawings in which—

20 Figure 1 is a side elevation of a piston illustrative of the invention and showing the same within a cylinder;

25 Fig. 2 is a transverse vertical section through the piston;

30 Fig. 3 is a transverse horizontal section substantially upon the line III—III of Fig. 1;

35 Fig. 4 is a transverse section substantially upon the line IV—IV of Fig. 1;

40 Figs. 5 and 6 are side elevations of the piston showing modified forms of baffles in grooves in the piston wall, and

45 Figs. 7, 8 and 9 are perspective views of the different forms of baffles shown in Figs. 5, 6 and 1 respectively.

50 Engine pistons as ordinarily constructed are formed with a series of circumferential grooves within which are placed expansible rings. These rings expand outwardly into

contact with the wall of the cylinder forming a tight joint therewith and preventing leakage past the piston. Instead of employing expansible rings which have limited contact surfaces and are subject to rapid disintegration, it is proposed to so form the piston A itself that it will expand within the cylinder B and thus closely contact the wall thereof, obviating the necessity for 60 separate means for making a tight joint.

In order that the cylindrical wall of the piston may yield or may be capable of contraction so that it may be made of slightly greater diameter than the internal diameter 70 of the cylinder B in which it is to be placed, and may then be forced into the cylinder, causing the wall of the piston to yield inwardly, and by its resiliency, to expand as said cylinder wall and the wall of the piston 75 wear away in use, thereby maintaining close contact therewith, a piston, indicated as a whole by the character A, is formed with a comparatively thin cylindrical wall 1 having longitudinally extending grooves 2 at 80 opposite sides thereof opening through the face of the wall, said grooves being formed within inwardly projecting portions of the wall thereby providing an inwardly extending wall 3 at each side of each groove, with the inner edges of these groove walls 3 connected by a bottom wall 4. The thin piston wall is thus continuous and is not weakened by the groove or grooves 2 in its outer face, but because of the inwardly extending portions 3 of the wall, the piston is free to contract and expand in diameter, the walls 3 yielding to provide such contraction and expansion. Preferably, the grooves 2 while extending lengthwise of the piston, extend 85 at a slight angle to the axis of the piston or to the perpendicular and thus as the piston travels in its cylinder, these grooves are carried in an angular position relative to the travel of the piston and the edges thereof will not be liable to score the wall of the cylinder.

To close the upper ends of these grooves 2 so that they will not be in open communication with the cylinder chamber above 105 the piston, said piston is formed with a head 5 having an annular groove 6 in its edge to receive an ordinary split piston ring 7 and this head is connected to the cylindrical wall of the piston by a contracted portion 110 which forms a deep annular groove 8 adjacent the head 5. The longitudinal grooves

2 open at their upper ends into this deep annular groove 8 below the head 5 and thus while the grooves permit expansion and contraction of the piston walls they do not extend through the head and thus the head, together with the rings 7, prevents leakage past the piston through the longitudinal grooves 2.

To further insure against leakage through 10 the grooves 2, said grooves may be formed at intervals with transversely extending grooves 9 which are preferably semi-circular in longitudinal section and short in length. Within each transverse groove is placed a 15 semi-circular plate 10 which fits within the groove and extends across the groove 2 thus forming baffles for effectually closing the passage through said longitudinal groove.

As shown in Figs. 5 and 7, the longitudinal grooves 2 may be closed by spring members or baffles 11 which are formed substantially S-shape in longitudinal section so that they may be forced into the groove with their ends engaging opposite walls 25 thereof and held in close contact with said walls by their spring action. By the use of these spring baffle members, the necessity for forming the piston wall with the transverse grooves 9 is obviated.

30 In Figs. 6 and 8 a further modified form of baffle member is shown, said member comprising a spring plate 12 having both of its ends bent laterally in the same direction, as shown at 13, and intermediate its ends 35 the plate is formed with a transverse rib 14 extending laterally from the plate in a direction opposite to that in which the ends 13 extend. These baffle members have an overall width which is slightly greater than 40 the width of the slot 2 and thus when they are forced into the slot, the plate will be deflected slightly, bending between its ends and by its spring action holding the ends 13 and the rib 14 in firm contact with opposite walls of the groove. Whichever form 45 of baffle is employed, the longitudinal grooves will be effectually closed thereby against the leakage of fluid therethrough and these baffles will not interfere with the 50 contraction and expansion of the longitudinal grooves, the side walls 3 of which will always have sufficient resiliency to impart an expanding action to the cylindrical wall of the piston and hold it in close contact 55 with the wall of the cylinder in which it operates.

When such a piston is used in the construction of internal combustion engines, it may be found desirable to form the wall 1

with shallow parallel annular grooves 15 60 which are each formed with an upper side or wall extending inwardly at right angles to the outer surface of the piston wall 1, forming therewith a right angle shoulder 16, the lower side of the groove meeting the 65 inner end of the upper wall thereof and extending downwardly and outwardly therefrom. Annular oil grooves are thus formed in the surface of the piston wall and the sharp angular upper shoulders 16 of these 70 grooves serve to scrape the oil from the cylinder wall and prevent its working up past the piston.

Obviously, pistons may be constructed 75 having other forms than that shown in the drawings, which forms may embody a piston wall having a groove therein providing yielding portions at the sides of the groove permitting expansion and contraction of the piston, and all such modifications are 80 contemplated herein, I do not therefore limit myself to the particular construction or arrangement of parts shown.

Having thus fully described my invention 85 what I claim is:

1. A piston including a cylindrical wall having an annular exterior groove near its upper end of greater depth than the thickness of said wall and formed with a portion extending inwardly from the wall and provided with a longitudinal groove opening through the outer face of the wall and opening at its upper end into said annular groove, whereby an imperforate cylindrical wall is provided which may yield, due to 90 the yielding of said walls of the longitudinal groove.

2. A piston including a head and a cylindrical wall depending from the head, said cylindrical wall being contracted adjacent said head to form a deep annular groove in said wall and said wall being also formed with a longitudinally extending rib projecting inwardly from the wall and extending from said contracted portion to the lower end of the wall, said rib being formed with a deep groove opening at one end into the annular groove of the wall and opening at 100 its outer side through the outer side of the wall throughout the length of the rib, and 105 baffling means within the groove of the rib.

In testimony whereof I affix my signature in the presence of two witnesses.

HENRY SCHMITT.
